CLAIM

The ornamental design for a housing for a mobile computing device, as shown and described.

DESCRIPTION

FIG. 1 is a front view of a housing for a mobile computing device;

FIG. 2 is a rear view of a housing for a mobile computing device;

FIG. 3 is a right side view of a housing for a mobile computing device;

FIG. 4 is a left side view of a housing for a mobile computing device;

FIG. 5 is a top end view of a housing for a mobile computing device;

FIG. 6 is a bottom end view of a housing for a mobile computing device;

FIG. 7 is another front view of a housing for a mobile computing device in a closed position;

FIG. 8 is another rear view of a housing for a mobile computing device in a closed position;

FIG. 9 is another right side view of a housing for a mobile computing device in a closed position;

FIG. 10 is another left side view of a housing for a mobile computing device in a closed position;

FIG. 11 is another top end view of a housing for a mobile computing device in a closed position; and,

FIG. 12 is another bottom end view of a housing for a mobile computing device in a closed position.

The broken line showing of the keypad in FIG. 1 is directed to environment and is for illustrative purposes only; the broken lines and the space around the broken lines form no part of the claimed design. The solid line that defines the area in which the broken line keys are shown represent the boundary of the claimed design.
